UNITED STATES PATENT OFFICE.

CARWITT E. MYERS, OF IRENTON, MISSOURI, ASSIGNOR OF ONE-HALF TO GEORGE D. ASH, OF LANSING, MICHIGAN.

AUTOMATIC RINGING MECHANISM FOR TELEPHONE SYSTEMS.

1,209,478.

Specification of Letters Patent. Patented Dec. 19, 1916.

Application filed August 30, 1913. Serial No. 787,533.

To all whom it may concern:

Be it known that I, CARWITT E. MYERS, a citizen of the United States, and a resident of Ironton, in the county of Iron and State of Missouri, have invented a new and useful Improvement in Automatic Ringing Mechanisms for Telephone Systems, of which the following is a specification.

My invention relates to improvement in automatic ringing mechanism for telephone systems, consisting in the combinations, constructions and arrangements herein described and claimed.

An object of my invention is to provide a ringing mechanism for telephone lines, which is automatic to this extent, that when a ringing key is pushed, the device will serve to effect certain current connections, for the sending of an alternating current to the sub-station, to effect the ringing of the signal.

A further object of my invention is to provide a device of the type described, which dispenses with the necessity of using a constantly rotating generator for the ringing current at the sub-station, or for using batteries to keep in operation the ordinary pole changers.

A further object of my invention is to provide an automatic ringing device which is in operation only during the time that the ringing is being done, thereby economizing in current and power.

Other objects and advantages will appear in the following specification and the novel features of the invention will be particularly pointed out in the appended claims.

My invention is illustrated in the accompanying drawings, forming part of this application, in which—

Figure 1 is a diagrammatic view showing the circuit connections, Fig. 2 is a side view of the vibrator, Fig. 3 is a plan view of the vibrator shown in Fig. 2, Fig. 4 is a face view of a relay, and Fig. 5 is a side view of the relay shown in Fig. 4.

Referring now to Figs. 2 and 3, I have shown therein a vibrator which consists of a base 40, upon which is mounted a standard 41 bearing the magnets C. The latter has an armature P² which is disposed on the vibrator arm E, pivotally mounted at K² and bearing an adjustable weight S on one end. The opposite end of the vibrator E is provided with a contact K' arranged to en-

gage an adjustable contact screw K. Secured to the armature P² is an arm P³ bearing a contact I arranged to engage a contact I' carried by a contact screw I³. A spring L is attached at one end to an adjusting screw L' and at the other to the armature P². Secured to the vibrator arm is a cross member S', the ends of which are slotted to permit the entrance of spring arms G and G'. The former is carried by a binding post 31 borne by a support 31^a, and the latter by a binding post 31^a on a support 31^b. Each of the arms G and G' is provided with a platinum contact near its central part. The platinum contact borne by the arm G is arranged to engage the terminals b' and b⁴ of the contact screws B' and B respectively mounted on supports B⁶ and B⁸ respectively, while the platinum contact on the upper arm G' is arranged to engage the contacts b² and b⁸ on the contact screws B² and B⁸, respectively which are carried on supports B⁹ and B¹⁰ similar to those shown at B⁶ and B⁸. It is obvious that when the arm E moves downwardly the lower contacts will be engaged, but when it moves upwardly the upper contacts will be engaged.

Referring now particularly to Figs. 4 and 5, I have shown therein magnets F whose armature F' is carried by an arm y² pivotally mounted at G² on a support G³ and provided with a contact y' arranged to engage a contact y carried on a support G⁴. The armature F' is normally held in a retracted position by means of a spring Z connected to an adjustable screw Z'.

The remaining apparatus of the telephone system is that in ordinary use and constitutes no part of my invention, except in so far as it coöperates with the apparatus just described. The description of the rest of the system and of the arrangement for automatic ringing will best be understood by taking a specific example of the operation of the device.

Let us consider now Fig. 1. a, represents a ringing key which, when pressed, serves to connect a circuit from the battery X at the left of the figure, this circuit being as follows: from battery X over wire 3^a to terminal R⁴, 105 thence through wire 3, contact spring G, platinum point w, b' (the contacts w and w' being held against the upper contacts b' and b⁸ by the tension of the spring L) wire 6^a, wire 6^a, coil F, wire 6^b, terminal R, wire 1, 110

ringing key a , through the switch board cord a' , plugging jack a^2 , and then through the line 1^a , through the windings n of the subscriber's station u , then back through the wire 5^a to the plugging jack a^2 , cord a' , to the ringing key a , thence through wire 2 to the terminal R' , wire 5^a , terminal b^3 , contact w' , arm G' , wire 4 , relay R^5 , wire 4^a , to battery. The circuit just traced is called for purposes of convenience, circuit No. 1. At the instant that the ringing key a is pressed, which closes the circuit just described, the magnet F will be energized, thereby pulling down the armature F' and closing the contacts 15 y', y . This causes current to flow from the vibrator battery X' to the binding post R^2 , wire 8 , contact y , contact y' , terminal y^2 , terminal 8^2 to vibrator standard K^2 , vibrator arm E , contact spring P' , platinum points 20 I, I', P^2 , wire 10 , to the windings of the magnets C , wire 9^a , to terminal R^3 , and thence to battery X' . For convenience I have termed this circuit No. 2.

The energization of the magnets C causes 25 the armature P^2 to be pulled downwardly, but through the medium of the cross arm S' which is carried by the vibrator arm E , contacts w and w' are shifted from the upper contacts b' and b^3 to the lower contacts b^4 30 and b^2 , respectively. The shifting of these contacts causes the relay F to become de-energized, thereby breaking the circuit through the coil C . The adjustable screw K^{2a} touches K' on a spring K^3 carried by 35 the arm E . This closes the vibrator circuit again over the battery X' , binding post R^2 , wire 9 , terminal K^{2a} , contact K , contact K' , arm E , P^2 , contacts I, I', P^2 , wire 10 , coil C , wire 9^a , binding post R^3 .

40 At the instant that circuit No. 2 above described is closed, the movement of the armature P^2 causes the breaking of the circuit of the coil C at $I—I'$. This will cause the arm E to vibrate, the movement of the vibration 45 of the arm being dependent upon the position of the adjustable weight S . The shifting of the platinum contacts w and w' , as heretofore described, from the lower contacts to the upper, causes a change of polarity 50 of the terminals R and R' , and this change of polarity results in the ringing of the signal bell at the station of the circuit No. 1. It will be observed that in tracing this circuit both of the terminals R and R' 55 are involved and that when the vibrator arm E is up, current will flow in one direction, and when it is down, it will flow in another direction.

60 It will be seen that I have provided a device by means of which current is supplied to the terminals for ringing the signal to telephone the sub-station only at such times as the ringing is actually being done. At other times the current is being conserved 65 and this, as stated before, obviates the neces-

sity of employing constantly rotating generators or batteries, which keep in operation the ordinary pole changers.

The device is simple in operation and is not liable to easily get out of order.

70

I claim:

1. In a telephone system, a central station provided with a pair of terminals, a relay at said central station, a vibrator arm having a pair of movable contacts, a source of current having one pole connected to one of said movable contacts, the other pole being connected to the other of said movable contacts, a pair of stationary contacts adapted to be engaged by each of said movable contacts, one contact of each pair of said stationary contacts having electrical connection with one of said terminals, the other stationary contact being connected with the relay coil on one side, the opposite side of the relay coil being connected to the other terminal, a vibrator coil controlled by the relay, a portion of the control circuit including said vibratory arm, a second source of current for energizing said vibrator coil, and means for short circuiting said vibrator coil across said relay during the reciprocatory movement of the vibrator arm.

2. In a telephone system, a central station provided with a pair of terminals, a relay at said central station, a vibrator arm having a pair of movable contacts, a source of current having one pole connected to one of said movable contacts, the other pole being connected to the other of said movable contacts, a pair of stationary contacts adapted to be engaged by each of said movable contacts, one contact of each pair of said stationary contacts having electrical connection with one of said terminals, the other stationary contact being connected with the relay coil on one side, the opposite side of the relay coil being connected to the other terminal, a vibrator coil controlled by the relay, a portion of the control circuit including said vibratory arm, a second source of current for energizing said vibrator coil, and means for short circuiting said vibrator coil across said relay during the reciprocatory movement of the vibrator arm, said means comprising a contact on said vibrator arm, a stationary contact engaged by said last named contact, and a connection between said last named stationary contact and said second named source of current.

3. In a telephone system, a central station provided with a pair of terminals, a relay at said central station, a vibrator arm having a pair of movable contacts, a source of current having one pole connected to one of said movable contacts, the other pole being connected to the other of said movable contacts, a pair of stationary contacts adapted to be engaged by each of said movable contacts, one contact of each pair of said sta-

130

- tionary contacts having electrical connection with one of said terminals, the other stationary contact being connected with the relay coil on one side, the opposite side of the relay coil being connected to the other terminal, a vibrator coil controlled by the relay, a portion of the control circuit including said vibratory arm, a second source of current for energizing said vibrator coil, and means for short circuiting said vibrator coil across said relay during the reciprocatory movement of the vibrator arm, said means comprising a contact on said vibrator arm, a stationary contact engaged by said last named contact, and a connection between said last named stationary contact and said second named source of current, and means for adjusting the rate of vibration of the arm.
- 20 4. In a telephone system, a central station provided with a pair of terminals, a relay at said central station, a vibrator arm having a pair of movable contacts, a source of current having one pole connected to one of said movable contacts, the other pole being connected to the other of said movable contacts, a pair of stationary contacts adapted to be engaged by each of said movable contacts, one contact of each pair of said stationary contacts having electrical connection with one of said terminals, the other stationary contact being connected with the relay coil on one side, the opposite side of the relay coil being connected to the other terminal, a vibrator coil controlled by the relay, a portion of the control circuit including said vibratory arm, a second source of current for energizing said vibrator coil, means for short circuiting said vibrator coil across said relay during the reciprocatory movement of the vibrator arm, said means comprising a contact on said vibrator arm, a stationary contact engaged by said last named contact, a connection between said last named stationary contact and said second named source of current, and means for adjusting the rate of vibration of the arm, said adjusting means comprising a weight shiftable along said arm, and means for securing the weight in its shifted position. 50
